BOWLING GAME BALL DELIVERY DEVICE

Evard A. Hayden, Desplaines, Ill.

Application November 5, 1945, Serial No. 626,645

6 Claims. (Cl. 273—38)

1

This invention relates in general to a bowling game and is more particularly described as a ball delivery device in which conditions similar to those in an actual standard bowling game are simulated.

An object of the invention is to provide means for delivering a bowling ball with a twisting or turning movement to give the ball a spin in either direction as it moves down the alley.

A further object of the invention is to provide new and improved means for engaging, releasing and imparting more or less speed to a bowling ball for a toy bowling game.

Other objects of the invention will appear in the specification or will be apparent from the accompanying drawings in which

Fig. 1 is a perspective view of a toy bowling game in accordance with this invention set up for use but with the pin spotter in pin engaging position;

Fig. 2 is a sectional view showing a connecting joint for the alley as taken on the line 2—2 of Fig. 1;

Fig. 3 is a sectional view as taken on the line 3—3 of Fig. 5 showing the pins with the pin spotting means in place;

Fig. 4 is a sectional view illustrating the construction and variable movement of the ball delivery means;

Fig. 5 is a longitudinal sectional view of the pin spotting means as shown in Fig. 1;

Fig. 6 is a transverse sectional view as taken on the line 6—6 of Fig. 4; and

Fig. 7 is a sectional view illustrating the ball holding and releasing means.

In a toy bowling game it is difficult to provide a construction which will actually represent and resemble the conditions and problems as they appear in an actual bowling game. This may be due primarily to the fact that the pins, the alley or the ball are not truly representative of the proper proportions and sizes of the other parts and elements of the game. In the present game the alley, pins and the ball are intended to be proportional and accurately representative of the sizes and proportions of the parts as actually used. In addition, a simple pin spotting device is used in properly locating and positioning the pins so that strikes, railroads, spares, and splits may be obtained as in the actual playing of a full size game. Perhaps the greatest improvement is in the means for simulating the actual delivery of a bowling ball, as to speed, spinning of the ball in either lateral direction and modifying the ball delivery. All of these conditions can

2

be changed at will depending upon the desire of any particular player.

Referring now more particularly to the drawings, a bowling alley 10 in accordance with this invention, may consist of a single unitary length of board 11, which is preferably wall board of the composite type but may be of any suitable material which is not subject to warping and it is supported and strengthened at its side edges by rails 12 of wood or the like secured thereto in any suitable manner as by fastening screws 13 inserted through the board into the supporting rails. End and cross pieces 14 and 15 are also provided at suitable spaced distances to hold the board firmly in position. In one preferred size of the game the alley is about 12 feet or slightly more in length and if desired it may be divided in two sections as shown in Figs. 1 and 2, connected at their juncture by bolts 16 which extend through adjacent end pieces 14, the sections being accurately aligned by dowel pins 17 set up into corresponding openings 18 in the end pieces.

Adjacent each end of the alley is a support comprising a pair of legs 19, each secured to one of the side rails by fastening bolts 20 and the legs of each pair being connected by a cross brace 21. A simple levelling device is mounted at the lower end of each pair of legs and comprises a bottom cross piece 22 having a transverse slot 23 at each end through which it is connected to the lower extremities of the legs 19 by bolt and wing nut fastening devices 24, the arrangement being such that either end of the cross piece 22 may be adjusted relative to its adjacent leg to raise or lower that side of the alley when the cross piece extends below the end of the leg. With this arrangement either end of the alley may be separately adjusted for levelling purposes which makes it possible to properly set up the alley on an extremely uneven ground.

Secured to each side rail 12 and projecting outwardly therefrom is a longitudinally extending strip 25 having a groove 26 in its upper face to form a side gutter in which balls will run when they pass off of the alley. These strips are secured to the side rails by fastening bolts or screws 27 and supporting blocks 28 are also located at intervals suitably secured in place below the strips 25 for additionally holding them in place. At the end of the alley are a number of bowling pins 30, ten in number for a regular bowling game which are preferably spotted or accurately positioned with respect to side boards 31 and a back board 32. Between the side boards and the alley the side gutters 26 extend into wider side

spaces 33, and between the end board 32 and the end of the alley is a pit 34 comprising a bottom board 35 secured to the lower edge of the adjacent end board 14 and also to the lower edge of the back board 32, as shown more clearly in Fig. 5. Into this pit 34 the pins may be swept or deposited, which have been knocked down by the first ball of each pair of balls constituting a bowling frame for one player. The remaining pins which are standing may then be knocked down by the next ball. After the pins are all knocked down or to properly position them at any time, a pin spotting device is provided which comprises a block 36 having a plurality of perforations 37 therein preferably slightly bevelled from the top downwardly and outwardly so that the block will pass easily over the largest portions of the pins 30, positioning them in proper locations on the alley when the block is moved downwardly thereover or when the block is moved downwardly and the pins are inserted from the top therethrough. This block is supported from the back board 32 by a pair of arms 38 connected thereto and each having a hinge 39 connecting it with the back board 32 at the bottom of a slot 40 extending downwardly from the upper edge of the back board so that when the pin spotting block is moved upwardly it will be positioned above the back board entirely out of the way of the pins and constituting a further extension of the back board to prevent the pins from being knocked outwardly at the end of the alley.

At the front end of each gutter strip 25 is an end block 41 so that when a bowling ball is returned from the pit end of the alley by rolling it down the gutter, it will be engaged and held in position by the block 41 so that it may be taken therefrom by the bowler. At the bowling end of the alley is a ball delivering device comprising a frame having side pieces 42 with upper and lower connecting cross-pieces 43 and 44. The lower end of each side piece is pivotally connected at the outer side of its side rail 12 by a bolt 45 which extends through them with a wing nut 46 at the outer end of the bolt so that the entire frame may be adjusted at various angles either vertically, inclined slightly forward, or inclined slightly rearward to modify the ball delivery, if desired.

Mounted upon the upper crosspiece is a collar 47 adapted to rotate freely thereon and to be moved lengthwise of the cross piece as desired. Attached to the collar as by means of an eyelet 48 is a flexible cord or support 49 having a ball support 50 at its lower end in the form of a cotter pin having straight extremities which tend to diverge slightly at their outer ends. A ball 51 is formed with an axial opening 52 of sufficient length to receive the outer end of the cotter pin therein, the divergence of the extremities of the cotter pin being such that they must be compressed slightly in order to insert them into the opening 52 of the ball thereby supporting the ball for lifting it by means of the cord and the cotter pin but readily disengaged therefrom if a slight jerk is given to the cord. This slight jerk is imparted for example by raising the ball and cord from the frame as shown in the broken outline in Fig. 1 and allowing the ball to swing downwardly until the cord or flexible member 49 engages the lower cross piece 44 which jerks the supporting cotter pin 50 outwardly from the ball but allows the ball to continue down the alley to engage the pins.

In practice the ball is raised from the frame at the end of the flexible cord and is held lightly in

the fingers of one hand or if desired in the fingers of both hands. The extent to which the ball is raised determines the speed at which it is thrown down the alley and if too much speed is given, the ball will be disengaged from its support and will bounce upon the alley out of control.

By raising the ball with the fingers to a desired height and then allowing it to slip out of the fingers, the flexible member will then contact with the lower cross piece 44 and the ball will roll forwardly at the desired speed.

If it is desired to modify the ball delivery, the frame may be inclined slightly forward from an upright position or inclined rearwardly from its intermediate upright position. A slight twist may also be given to the ball as it leaves the fingers which will impart the same twist to the ball as it rolls down the alley, thus causing the ball to have a slightly turned path depending upon the direction of rotation imparted to it. For accurately throwing the ball to engage a single pin or a number of pins the collar 47 may be moved along the cross piece 43 and the ball may be moved laterally with respect to the collar, when the ball is raised, so that the ball may be thrown at an angle from one side of the alley as for example to pick up either end pin in the back row by an across-the-alley shot.

With this construction the cross and side pieces may have a sufficiently loose connection so that it is also possible to distort the frame slightly, as for example, by moving one side piece forwardly to a greater extent than the other which will correspondingly move the cross pieces 43 and 44 which will produce a corresponding variation in the movement of the ball itself depending also upon the twisting and other movement which is given to the ball in the ordinary operation.

An actual bowling game with great variation of movements of the ball, with accurate sighting of the ball in raised position and accurate positioning of the ball by means of the flexible support and the collar is provided, simulating the actual conditions which are found in a regulation bowling game. The alley may be accurately set up and levelled and the pins are positioned by the pin spotting device so that each contestant will be subject to the same conditions as nearly as possible as in a regulation game of bowling. The play and counting of the game are the same as in any regulation game and although the game of ten pins is represented as set up by the pin spotting device, any number of pins as commonly used in other bowling games may also be set up and accurately spotted in the same manner.

When a game is finished the supports for the alley may be quickly disconnected and placed or packed closely with respect to it, the bowling frame may also be disengaged, and if the alley is made in sections, the parts may be disconnected and placed together compactly to occupy a minimum of space for storage and shipment.

Various changes in construction, combination and arrangement of the parts may be made without departing from the spirit and scope of the invention.

I claim:

1. In a bowling game, a ball delivery device for a ball having a bore extending from the outer surface and comprising a frame pivotally mounted at its lower end at the sides of an alley for adjustment forwardly and rearwardly with respect to a central upright position, an upper cross piece in the frame, a lower cross piece in

the frame spaced above the alley, a flexible member secured to the upper cross piece and extending below the lower cross piece, and a cotter pin at the lower end of the flexible member with its separable ends insertable in the bore of the ball and adapted to frictionally engage the sides of the bore, and the ball being delivered by raising it from the frame supported by the flexible member and releasing them, and allowing the ball to swing downwardly to engage the flexible member with the lower cross piece to discharge the ball from the cotter pin.

2. In a toy bowling game, a ball delivery means for a ball having a bore extending inwardly and for imparting a curved path to the ball as it is delivered, said means comprising a frame mounted at the sides of the alley and extending upwardly therefrom with upper and lower cross pieces, the ball being less in diameter than the distance of the lower cross piece above the alley, a cotter pin frictional ball holder extending into the bore of the ball, a flexible cord member adapted to be twisted connected at its lower end to said cotter pin and connected to the upper cross piece at its upper end, the ball being delivered by raising it from the frame with the flexible member and allowing it to swing downwardly to contact the flexible member with the lower cross piece, dislodging the ball from the frictional holder, and the flexible member permitting a manual twisting movement of the ball and the member which is reversed as the ball is delivered to impart curved movement to the ball as it moves along the alley.

3. In a bowling game, ball delivery means for a ball having an inwardly extending bore, said ball delivery means comprising a frame pivoted at its lower end at the sides of an alley, the frame comprising two side pieces and upper and lower cross pieces, a support movable lengthwise on the upper crosspiece, a flexible member secured at its upper end to said support and depending below the lower cross piece, and a cotter pin frictional ball holding member at the lower end of the flexible member to engage in the bore of a ball, the ball being delivered by raising it from the frame at the end of the flexible member and allowing them to swing downwardly until the lower portion of the flexible member engages the lower cross piece, thereby dislodging the ball from the holding member and impelling it along the alley.

4. In a bowling game, a ball throwing device for a ball having an inwardly extending bore and comprising a pair of side pieces individually pivoted at the lower ends at the sides of an alley, a cross piece connecting the upper ends of the side pieces, a cross piece connecting the lower ends of the side pieces, the cross pieces being loosely mounted in the side pieces to permit a limited separate adjustment of the side pieces with respect to each other to correspondingly incline the cross pieces transversely of the alley, a frictional holder insertable in the bore of the ball, a flexible cord member secured to the frictional holder, and a support slidable on the upper cross piece to which the upper end of the flexible cord member is connected, the said cross pieces being adjustable with the side pieces to impart an angular across the alley movement to the ball from said device.

5. In a bowling game, a ball having an inwardly extending outer bore, a throwing device for one end of an alley, comprising a pair of

side pieces each adapted to be pivoted at its lower end to one side of the alley and inclinable forwardly and rearwardly from an upright position, upper and lower cross pieces connecting the side pieces, a support slidable longitudinally on the upper cross piece and freely rotatable thereon, a flexible member connected at its upper end to the support and adapted to be twisted and returning to its original condition when released, a cotter pin ball holding device at the lower end of the flexible member inserted into the bore of the ball and frictionally engaged therein, the ball being raised with the flexible member extended and allowed to swing against the lower cross piece to dislodge the ball from the frictional holding device to impel the ball along an alley, the path of the ball being selected by moving the upper holding support to any desired position along the cross piece and a curve being imparted to the ball on the alley by turning the ball with the flexible member before they are released for imparting movement thereto.

6. In a toy bowling game, a ball throwing device comprising means for frictionally and releasably engaging a ball, an inclinable frame having side pieces pivotally mounted at the lower ends at the sides of an alley, a cross piece connecting the upper ends of the side pieces, a cross piece connecting the lower ends of the side pieces above the alley, the frame being adjustable from an upright position forwardly or rearwardly, a flexible cord attached at its upper end to the top cross piece and adapted to be twisted and to return to its original condition when released and the lower end connected to the frictional and releasable means for engaging a ball, the ball being delivered by raising it from the frame with the flexible cord and allowing it to swing downward to contact the flexible cord with the lower cross piece, dislodging the ball from the frictional ball engaging means, the rolling movement of the ball being modified by the forward or rearward inclination of the frame when the ball is released from the flexible cord, and the cord being rotatable to impart a curved movement to the ball as it moves along the alley.
